UNITED STATES PATENT OFFICE.

CHARLES A. LAPWORTH, OF WEST BRIDGEWATER, MASSACHUSETTS, ASSIGNOR TO THE LAPWORTH WEBBING COMPANY, OF BROCKTON, MASSACHUSETTS.

ELASTIC FABRIC.

1,195,036.

Specification of Letters Patent. Patented Aug. 15, 1916.

Application filed October 18, 1915. Serial No. 56,423.

To all whom it may concern:

Be it known that I, CHARLES A. LAPWORTH, a citizen of the United States, residing at West Bridgewater, in the county 5 of Plymouth and State of Massachusetts, have invented certain new and useful Improvements in Elastic Fabrics, of which the following is a specification.

This invention has for its object the production of a selvaged elastic fabric having the face and back of different designs, the back and selvages presenting a plain or cotton weave with alternate warp threads passing alternately under and over the adjacent 15 wefts.

A further object of this invention is to produce a novel elastic fabric the face of which presents alternating diagonal raised or twilled portions forming a wave-like design having the anticlinal and synclinal axes thereof disposed over the elastic warps.

The elastic warps employed are woven under tension, and when released contract and cause the face warps to untwist thereby 25 giving to the twilled or raised portion of the design a soft plush-like appearance. In the fabric produced by this invention the weft employed crosses the rubber warp on opposite sides at alternate picks, thereby 33 binding the rubber at every pick and preventing it from materially relaxing in the fabric with relation to the fiber warps after the fabric is removed from the loom.

The fabric to be herein more particularly 35 described may contain face and back warps of the same or different colors. The face and back are united by binder warps, two of which are preferably employed between adjacent elastic warps. In the manufacture 40 of the body of the improved fabric the face warps are so controlled by the harness-frames that each face warp is up for five picks where the twill is to be produced, and then down for one pick, up for one pick 45 and down for one pick to produce the plain woven portion of the face. The entire pattern is woven in eight-time motion, or in motion where eight sheds or eight picks are required to produce the pattern, three picks 50 of the eight aiding in the formation of the plain portion of the face and the fabric and five picks aiding in the formation of the raised or twilled portion thereof so that it presents the appearance above referred to.

55 The back of the fabric, which may be

woven in the same order as the face, as is commonly done, in the preferred form of my invention, is woven to produce a plain pattern as will be later described. The selvage is also preferably woven in the plain 60 or cotton weave to produce a firm wearing edge.

My invention will be more clearly understood by reference to the accompanying drawings in which like characters are used 65 to designate like indicia representing threads throughout the several views thereof.

Figure 1 is an enlarged detail view of the face of the fabric. Fig. 2 is a spot layout of 70 the design of my invention. Fig. 3 is a cross sectional view of the fabric showing the warps as they appear at the first shed or first pick. Figs. 4 to 10 inclusive are like views of the second to the eighth pick inclusive. Fig. 11 is a like view of the first 75 shed of the repeat, it being the same as Fig. 2. Figs. 12 and 13 are longitudinal sections of a fabric woven in accordance with my invention.

The face warp comprises four series of threads 8, 9, 10 and 11; 8 designating one series, 9 another series, etc., each series being controlled in the loom by heddles of different harness-frames, series 8 being controlled by one, series 9 being controlled by another, and so on, four harness-frames being employed for the face warp. The india rubber warps *r* are all under the control 85 of one separate harness-frame. The series of back warps 4 and 5 are controlled by the heddles of two different harness-frames, all the series of threads designated by like numbers being controlled by the same harness-frame.

In weaving the selvage, the back warps 4 and 5 and the rubber warp shed exactly as in the main body of the fabric, while the warp *w* comprising the face design is woven directly the reverse of the back warp, 100 thereby giving a plain or cotton weave to both the front and back of the selvage.

Referring to Fig. 2 the shaded groups of lines *G* extending horizontally designate the back weft, while the shaded groups of 105 lines *H* running vertically designate the back warp. Likewise the horizontally extending unshaded spaces each designate a face weft while the vertically extending unshaded spaces designate the face warp. It 110

will now be apparent from a careful study of this layout that the filled black squares A indicate the relative position at which a face warp is raised over a face weft to produce 5 the twilled portion of the fabric. In like manner the circles B indicate that the face warp is raised over the back weft. The unfilled diamonds C indicate the passage of the binder thread over a back weft while the 10 filled diamonds D indicate the passage of the binder over the face weft at that point. Throughout this view the crosses E indicate that the back warp at that point is raised to pass over the back weft. From the foregoing 15 it is apparent that the blank spaces indicate the relative points at which the weft appears on the surface of the fabric, and in like manner the filled-in squares and diamonds represent the general outline of the design.

Referring now more particularly to Figs. 3 to 11, it will be seen that the face warp 11 is raised for the first three picks, is down for the fourth pick, up for the fifth pick, 25 down for the sixth pick and up for the eighth and ninth picks and for the first repeat pick. The face warp 10 is up for the first pick, down for the second pick, up for the third pick, down for the fourth pick and then up for picks 5 to 8 inclusive and for 30 the first repeat pick of the pattern. The face warp 9 is up for the first pick, down for the second pick, up for picks 3 to 7 inclusive and then down for the eighth pick 35 and up for the first repeat. The face warp 8 is up for the first five picks, down for the sixth pick, up for the seventh, down for the eighth, and up for the first repeat. The back warps 4 and 5 are each up for one 40 pick and then down for three picks, thereby producing a plain or cotton weave on the back of the fabric. The binders 6 and 7 are alternately up for two picks and then down for two picks. The rubber warp r is up for 45 one and then down on the next pick, alternately.

In Figs. 12 and 13 I have represented the different warp and binder threads of the face and back of the fabric. From the 50 showing in these figures, the construction of the completed fabric will be more readily understood and the startings of the diagonal lines of plain and of twilled weaving will also be apparent.

55 The diagonal, or wave-like lines of plain and twilled weaving not only give an attractive appearance to the fabric, when in its normal condition, but are so located with their anticlinal and synclinal axes disposed 60 respectively above adjacent elastic warps

that they extend at substantially an angle of forty-five degrees therebetween and upon stretching the fabric the design is not destroyed, but is in reality made more pronounced by reason of the separation of the 65 adjacent or interfitting portions of the design, thereby more clearly showing each individual portion thereof.

While I have described this invention as being for an elastic fabric, it is evident that 70 I may, if so desired, construct a corded fabric according to the same plan of weaving, one half of each individual design being formed between adjacent rubber warps or cords.

Having thus described my invention what I desire to claim is:—

1. An elastic fabric having reversely twilled portions on the face thereof, in opposite sides of each elastic warp, said twilled 80 portions extending diagonally between adjacent elastic warps to produce a wave-like design extending transversely of the fabric.

2. An elastic fabric having twilled portions on the face thereof forming a wave- 85 like design extending transversely of the fabric, said design having its anticlinal and synclinal axes disposed substantially co-incident with the elastic warps.

3. A double elastic fabric having a plain 90 back and selvage, and woven to produce a wave-like design extending transversely of the fabric, said design having its anticlinal and synclinal axes disposed substantially over adjacent elastic warps.

4. In an elastic fabric woven in eight-time motion, a design having alternating crests and troughs extending across the fabric in one direction, and having elastic warps extending through the fabric at substantially right angles to the design, said elastic warps passing through the crests and troughs respectively of said design.

5. In an elastic fabric, a plurality of elastic warps, a design having the main 105 body thereof extending transversely of the fabric at substantially right angles to said elastic warps, said design being composed of a plurality of units or twilled portions each of which is formed between adjacent elastic 110 warps, the continuity of said twilled portions in a given direction on a given line terminating with the adjacent elastic warps between which it is formed.

In testimony whereof, I have hereunto 115 subscribed my name.

CHARLES A. LAPWORTH.
